Primary Examiner — T Chase Nelson*Assistant Examiner* — Jonathan J. Han(74) Attorney, Agent, or Firm — Banner & Witcoff, Ltd.(57) CLAIM

The ornamental design for a shoe, as shown and described.

DESCRIPTION

FIG. 1 is a front bottom perspective view of a shoe showing my new design;

FIG. 2 is a bottom view thereof; and,

FIG. 3 is a rear bottom perspective view thereof.

The broken lines within the five ground engaging elements represent tread grooves. The broken-line tread grooves and the unshaded areas within the ground engaging elements form no part of the claimed design. The broken lines depicting the remainder of the shoe show features that form no part of the claimed design.
